UNITED STATES PATENT OFFICE.

CLAUDE T. DAWES, OF JOHNSTOWN, NEW YORK.

REVOLVING DOOR.

1,273,463.

Specification of Letters Patent. Patented July 23, 1918.

Application filed January 11, 1916. Serial No. 71,419.

To all whom it may concern:

Be it known that I, CLAUDE T. DAWES, a citizen of the United States, residing at Johnstown, in the county of Fulton and 5 State of New York, have invented certain new and useful Improvements in Revolving Doors, of which the following is a full, clear, and exact description, such as will enable others skilled in the art to which it appertains to make and use the same.

My invention relates to an improvement in revolving doors, and has for one of its objects the provision of such a construction that entrance and egress can be more easily 15 effected than in the usual type of revolving door in which each of the fixed portions of the casing subtends an angle of about 90 degrees. It often happens in doors of the last-named type, when revolving rapidly, 20 with many people passing in both directions, that persons will refuse to enter a vacant space because of the insufficient time left after a person going in the opposite direction has stepped out of it. Many sections 25 thus pass by unoccupied at a time when the door should be used to the utmost extent. The result of my improved construction is to produce a door in which a straighter, shorter and easier course of travel for the 30 individual user is provided. The user will thus be prepared to step out in less time than in the case of the present type of revolving door, while less effort will be required on his part, since it will be necessary 35 to push the door a considerably less distance.

Another object of my invention is to provide means for effectually closing any direct passageway for the entrance of air into 40 the building in all positions of the rotatable parts of the door.

Other objects of my invention will be in part obvious and in part pointed out hereinafter.

45 The invention accordingly consists in the features of construction, combinations of elements and arrangement of parts which will be exemplified in the construction hereinafter set forth, and the scope of the application of which will be indicated in the following claims.

In the accompanying drawings, wherein are shown certain of various possible embodiments of this invention,

55 Figure 1 is a plan view, partly in section, showing one embodiment of my invention;

Fig. 2 is a view of a section taken along the line II, II of Fig. 1;

Fig. 3 is a view of a section taken along the line III, III of Fig. 1;

Fig. 4 is a side elevation of the top of a revolving door embodying my invention;

Fig. 5 represents a modification of the construction shown in Fig. 1, in which the fixed portions of the casing are placed in a 65 different position with respect to the wall of a building;

Fig. 6 is a view in section showing a modified form of my invention, in which three wings instead of four are used;

Fig. 7 is a plan view, showing a modified form of mechanism for controlling the operation of the door;

Fig. 8 is a side elevation of the top of a door embodying the modification of Fig. 7 75 and

Fig. 9 is a detail thereof.

Referring now to the drawings, in which similar reference characters relate to similar parts throughout the several figures, 1 denotes the spindle or the axis of the revolving portion of the door. To this spindle are attached wings 2, 3, 4 and 5 of any desired construction, and which, in the embodiment shown in Fig. 1, are disposed at right angles about the spindle 1. 6, 6 represent fixed casings connected to the sides of an opening in the wall 7 of a building. Each of the casings is composed of inner members 8 and outer members 9. In the embodiment 85 shown in Fig. 1, each of the members 6 subtends an angle of about 45 degrees instead of 90 degrees, as in the usual form of doors of this type. Also in this figure, each casing is placed tangentially at its 90 middle point to the opening in the wall of the building, while in the modification shown in Fig. 5, each casing is connected at one of its ends to the wall.

It will be seen that, with the above described construction, there will be periods during the rotation of the wings of the door in which there will be a free passage into the building. From observation I have concluded that when the wings are in the position shown in Fig. 1, the space between the outer edge of the wing 2 and the outer edge of the righthand casing 6, as well as the corresponding space on the other side of the door are unusable, and the time which it 110 takes the door to pass over them is lost. No person will be likely to attempt to enter the

space between the wings 2 and 3 when they are in the position shown in Fig. 1. Therefore, when the wing 2 reaches this position, the space between it and the edge of the 5 casing might just as well be completely closed, and my invention provides means for closing it, thereby making it unnecessary to extend the casing 6 through a greater angle than about 45 degrees. The requirements of 10 the member which closes the above mentioned opening are that it shall come out to meet the wing 2 when the latter is in the position shown in Fig. 1, just before the wing 3 passes out of contact with the 15 surface of the casing; otherwise there would be an open passageway into the building. It will be understood, of course, that the edges of the wings are provided with the usual pieces of flexible material, which 20 brush over the inner surfaces of the casing members to form a close-fitting joint, and prevent direct communication between the internal and external air.

As an illustration of one construction 25 which may be used for closing the opening in the doorway at proper times, there are shown two movable casings or arcs 10, each carried by two arms 11 and 12 of a spider at the top of the spindle of the door. The arcs 10 are adapted to pass into or out of the fixed casings 6, 6 through openings 13, 13 at the outer edges of the latter. As guides for the arcs 10, 10 there are provided rollers 14 of any desired 30 number and mounted in any suitable way upon the inside of the casings 6, 6. To retain the arcs 10, 10, within the casings 6, 6 until such times as it is desired they shall be released, a latch 15, one end 16 of which 35 is forced outward from the casing by means of a spring 17, is provided for each casing. The end 16 of the latch is adapted to be engaged by the flexible members 18 on the outer edges of the wings, or in case these 40 members do not possess the requisite stiffness, a stud may be placed on the edge of each wing in a position to engage the member 16 as the wing passes thereby.

For the purpose of moving the arcs 10, 10 45 out of the casings 6, 6 when the latches are disengaged from them, there is provided the construction shown most clearly in Fig. 2, in which 19 represents a hollow casing to which the spider arms 11 and 12 are attached. 50 This casing is placed about the pivot 20 of the spindle 1. 21 represents a spiral spring attached at its inner end to the pivot 20, as at 22, while its outer end is fixed to the casing 19, as at 23. This spring is wound in 55 such a manner that as the door rotates in the direction of the arrow, shown in Fig. 1, the tension of the spring will be increased by means to be hereinafter described.

For the purpose of adjusting the pressure 60 of the pivot 20 upon the spindle 1, the

former is screw-threaded, as at 24, through a plate 25, the latter being set in a recess in the block 26, which in turn is placed in the frame-work 27 at the top of the door. 28 represents a hexagonal recess in the block 26, and in which is fitted a hexagonal extension 29 on the end of the pivot 20. The purpose of this last described construction is to prevent the plug from turning when it is raised or lowered by altering the position 75 of the member 25. The latter member is adapted to be set in any desired position of adjustment by means of screws 30.

It will be obvious from the construction shown in Fig. 1 that as the door rotates in the direction of the arrow and the wings 2 and 4 approach their respective casings 6, 6, the arcs 10, 10 should be carried along with them, and finally latched within the casings until released at the time when the wings 2 and 4 occupy positions 90 degrees from those shown in Fig. 1, or when they occupy the 80 positions of the wings 3 and 5 respectively. As a means for causing movement of the arcs 10, 10 when the wings are rotated, devices of the construction shown in Fig. 3 are provided. Each device comprises a spring-pressed catch 31 mounted in any convenient manner upon a wing of the door, it being understood that there is one of these 85 catches upon each wing. Each catch comprises a plunger 32, to the upper end of which is attached a plug 33 having a conical end. The plunger and plug are adapted to slide up and down in the ends of a casing 34 surrounding them. The plug 33 is forced upwardly by means of a coil spring 35 placed within the casing 34 in the manner shown, the tension of the spring being adjusted by means of a lock nut 36 upon the 90 lower end of the plunger. 37 represents a projection placed upon the underside of the spider 11, so as to be engaged by the plug 33 when the wing passes beneath the spider. The spring 35 is adjusted to such a tension 95 that it will retain the plug 33 in contact with the projection 37 while the wings of the door are rotated through an angle of 45 degrees from the position shown in Fig. 1. The spider, and consequently the arcs 10, 10, carried thereby, will thus be carried along by the rotation of the wings until the arcs have been forced completely within the casings 6, 6, at which time the respective latches 15, 15, will engage notches 38, 38 in the arcs. Further motion of the wings will force the plugs 100 33, 33 downward against the action of the springs 35, 35 and under the projections 37, 37. The wings will thus pass on, leaving the arcs 10, 10 latched within the casings 6, 6. During the above described movement of the arcs 10, 10, the spring 21, in the spider, will be placed under tension, so that 105 when each latch 15 is released by a wing passing adjacent thereto, the spring in un- 110 115 120 125 130

winding will cause the arcs 10, 10 to move out of their respective casings 6, 6 in position to be engaged by the edges of the next succeeding wings as they reach the position 5 of wings 2 and 4 in Fig. 1.

To provide a close fit between the outer edges of the movable arcs 10, 10 and the flexible strips 18 carried on the edges of the wings, an extension 39 is formed on each arc. 10 Under some conditions of use, it may be desired to retain the arcs in their casings during the operation of the door, and to provide for this contingency, there is placed at the outer edge of each casing a latch 40 in the 15 form of a pin adapted when pushed in to engage an opening 41 in the arc 10 to retain the latter in place in the casing, irrespective of any movement of the latch 15.

There is shown diagrammatically in Fig. 20 5 an arrangement which is, in all respects, similar to that shown in Fig. 1, so far as the mechanism is concerned, but the casing members 6 are placed with one end of each adjacent to the wall 7. This arrangement 25 may be of advantage under certain conditions.

In Fig. 6 there is shown an arrangement in which three wings instead of four are used, the wings being placed at angles of 120 30 degrees apart. In this case, casing members 6', 6' are shown as subtending angles of 90 degrees each. This form of construction has the advantage of permitting two persons to pass through the door in each compartment, although the dimensions of the door may be substantially the same as in the usual form of door in which the casing members subtend angles of 90 degrees each, but in which there are four wings placed at right 35 angles. It is obvious that in the form of construction shown in Fig. 6 it is necessary to provide arcs 10', 10' for the same purpose as previously described; otherwise there would be a direct passageway into the building at certain positions of the wings. 40

To meet the different conditions arising when the modification shown in this figure is used, the two arcs 10', 10' cannot be suspended from opposite arms of the same 50 spider, as in the construction shown in Fig. 1, for the reason that when the left-hand arc 10' is extended the right-hand arc should be latched within its casing to provide a maximum opening between the edges of the two 55 casings. Furthermore, in the modification shown in Fig. 6 latches 15', 15' while occupying the positions shown, should not be released until the wings reach the ends 42, 42 of the casings 6', 6'. Therefore, there is 60 provided for each latch a rod 43 connected to a lever 16' in such a manner that when the latter is pressed inwardly against a spring 17' by any one of the wings the arc 10' held by the latch will be released. 65

In order that a second person in a com-

partment of the door may have some control over its rotation, a series of handles 44 is provided. These handles are attached to the pivot shaft of the door and extend into the compartments a convenient distance. 70

It is believed to be unnecessary to show a double spider construction such as would be suitable for supporting the arcs in the embodiment shown in Fig. 6, since apparatus of this nature could be provided in a variety of forms and arranged to be actuated in a manner similar to that previously described. 75

Having described the construction of certain embodiments of my invention the mode 80 of operation thereof may be briefly reviewed. A person desiring to pass through the door and finding the wings in the position shown in Fig. 1 will enter the compartment between wings 2 and 5, and proceed to push the former wing in the direction of the arrow. The catch 31 on the wing 2 will be in contact at this time with the projection 37 on the arm 11 of the spider, and thus the latter will be turned, 90 carrying with it the arc 10, which will be gradually pushed into its casing 6. At the same time, the motion of the spider will increase the tension of the spring 21 in the hollow portion 19 of the spider. When the 95 arc 10 has been completely returned within its casing, the latch 15 engages the notch 38, and since no further movement of the arc is possible, continued motion of the wings will force the plug 33 to pass beneath the projection 37 and the wing 2 will pass on with its flexible edge sweeping over the inner surface 8 of the casing 6. Finally the edge of wing 2 engages the arm 16 of the latch, causing the latter to release the arc 10, which 100 will, under the influence of spring 21, move out of its casing to meet the edge of wing 5, which, at this time, will occupy the former position of wing 2, as shown in Fig. 1. Further motion of the wings will enable the 105 user to pass out of the compartment in which he has been moving through the doorway. It will be understood, of course, that operations similar to those described above will occur simultaneously at the other side of the 110 door, regardless of whether or not another person is passing through in the opposite direction.

In Figs. 7, 8, and 9 is shown a modification of apparatus for controlling the motion 120 of the arcs 10 which are, as in the embodiment shown in the other figures, suspended from the arms 11 and 12 of a spider which is moved by a spring 21 as in Fig. 2. Wings 2, 3, 4, and 5, and fixed casings 6, 6 having 125 rollers 14, as in Fig. 1, are provided.

Above the door is placed the usual ceiling member 50, beneath which is a plate 51 for supporting certain apparatus to be described hereinafter. 130

22
 Mounted upon opposite arms of the spider in any convenient manner are plungers 52 each normally pressed upward as by means of a spring 53 against the surface of a track 54 secured to the under side of plate 51. A roller 55 is provided to reduce friction when the plunger moves relatively to the track 54 as it is caused to do by one of the wings of the door engaging the plunger when the 10 spider carrying the same has been brought to the position shown in Fig. 1, in which the arcs 10 are withdrawn from their respective casings. When in this position the plungers project into the path of the wings and motion of the latter causes the arcs to be carried into their respective casings. During 15 such movement the rollers traverse the tracks until each one comes underneath an aperture 56 cut in the plate 51 at the end of the 20 track. This occurs at the time when the arcs 10 have been returned completely within the casings.

Mounted within each aperture and hinged to the plate 51, as at 57, is a block 58 having 25 a recess 59 in its lower face. Connected to the block 58 is a lever 60, pivoted at 61 and having a downwardly extending extremity 62 passing through an aperture 63 in plate 51 and projecting into the path of the wings. 30 By means of a spring 64 the arm of the lever attached to block 58 is normally raised so that when the plunger comes under said block its spring 53 will raise the plunger into the aperture 56, thereby removing its 35 lower end from the path of the wings, thus permitting the latter to continue their rotation, but the spider is held in such a position that the arcs are completely within their respective casings.

40 When the wings that are traversing the inner surfaces of fixed casings 6, 6 are about to leave the same the arcs 10 should be carried into the position shown in Fig. 1. This is effected in the present modification 45 by a wing of the door engaging the extremity 65 of the portion 62 of the lever 60 thus tilting the latter sufficiently to cause block 58 to push the plunger 52 out of the recess 56, whereupon the spring 21 of the 50 spider will immediately cause the latter to assume the position of Fig. 1, carrying with it the arcs 10 to close the direct passageway through the door which would otherwise result when the wings passed from in contact 55 with their corresponding casing members. If desired a stop 66 may be provided to limit the amplitude of movement of lever 60.

In view of the foregoing description of 60 certain embodiments of my invention it will be seen that I have produced a structure fulfilling all of the objects and possessing all of the advantages as stated at the beginning of this specification. A person entering the door will not have to travel so far after he

passes the line of the building wall as in the 65 case of the ordinary construction, in which the casing extends within the building for an angle of 45 degrees. If the door is rotating at a somewhat rapid rate there is a 70 tendency for a person to hold on to the wing 70 in front of him for a considerable distance beyond the point where he may let go and step out. Most people push the door with the right arm, which is thus placed across the front of the body at the finish of the 75 push, and this renders somewhat more difficult the abrupt turn to the right which is necessary for a person to leave the door. In the case of my invention, a person can 80 pass out of a compartment in the door much easier than if forced to travel in a continued circular course to get around the edges of a casing, which, as in the usual construction, extends within the building a considerable distance. 85

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. 90

It is also to be understood that the language used in the following claims is intended to cover all of the generic and specific features of the invention herein described and all statements of the scope of the invention, which, as a matter of language, 100 might be said to fall therebetween.

Having described my invention what I claim as new and desire to secure by Letters Patent is:

1. In a revolving door, in combination, rotatable wings, fixed arcuate casings therefor, movable arcuate casings associated with said fixed casings, and means whereby said wings in rotating insure alternate predetermined movement of said movable casings therewith and reversely thereto. 105

2. In a revolving door, in combination, a rotatable element including radiating wings disposed at fixed angles, opposite casing walls therefor including slideable sections, 115 and means whereby said sections are caused alternately to slide with said wings and oppositely thereto during rotation of the latter in one direction.

3. In a revolving door, in combination, a 120 rotatable element having radial wings, opposite arcuate casing walls therefor including movable sections, and means whereby said sections are actuated by said wings successively during rotation to decrease intermittently the arcuate dimensions of said walls. 125

4. The combination in a revolving door, of

- a rotatable element having angularly disposed wings, a casing wall therefor including a movable section, and means to insure limited movement of said section in opposite 5 directions during rotation of said element in one direction.
5. A revolving door including, in combination, a rotatable element having a plurality of radially disposed wings at fixed angles, opposite arcuate casing walls therefor including relatively movable arcuate sections, and means to insure intermittent movement of said sections during rotation of said element for causing said casing walls alternately to 10 subtend equal and lesser angles with respect to said fixed angles.
6. In a revolving door, in combination, a plurality of rotatable wings, a casing comprising a casing member movable independently of said wings, and means whereby rotation of said wings effects movement of said movable member.
- 20 7. In a device of the character described, in combination, a fixed casing member, a movable casing member adapted to be moved longitudinally of said fixed member, and spring means adapted to effect relative movement between said casing members.
- 25 8. In a revolving door, in combination, a plurality of rotatable wings, a casing comprising a fixed member and a member movable relative to said fixed member and to said wings, and means adapted to effect movement of said movable member at predetermined times during the rotation of said wings.
- 30 9. In a revolving door, in combination, a plurality of rotatable wings, a casing comprising a fixed member and a member movable relative to said fixed member and to said wings, means adapted to effect movement of said movable member at predetermined times during the rotation of said wings, and means adapted to limit the extent 35 of such movement.
- 35 10. In a revolving door, in combination, a plurality of rotatable wings, a casing comprising a fixed member and a member movable relative to said fixed member and to said wings, means adapted to effect movement of said movable member at predetermined times during the rotation of said wings, and means adapted to render said first means ineffectual.
- 40 55 11. In a revolving door, in combination, a plurality of rotatable wings, a casing comprising a fixed member and a member movable relative to said fixed member and to said wings, and means urging said movable member to move in a predetermined direction.
- 50 60 12. In a revolving door, in combination, a plurality of rotatable wings, a casing comprising a fixed member and a member movable relative to said fixed member and to said wings, and means whereby movement of said wings effects movement of said casing in the reverse direction and increases the urging force of said first mentioned means.
- 65 13. In a revolving door, in combination, a plurality of rotatable wings, a casing comprising a fixed member and a member movable relative to said fixed member and to said wings, means urging said movable member to move in a predetermined direction, and means locking said movable member against such movement.
- 70 14. In a revolving door, in combination, a plurality of rotatable wings, a casing comprising a fixed member and a member movable relative to said fixed member and to said wings, means urging said movable member to move in a predetermined direction, means restraining said movable member against such movement, and means adapted, upon said wings assuming a predetermined position, to render said last mentioned means ineffectual.
- 75 15. In a device of the character described, in combination, a revolving door comprising a plurality of rotatable wings, fixed casings, casings each of which is movable longitudinally relative to one of said fixed casings and to said wings to permit 80 the edges of two oppositely disposed wings to simultaneously register with casing members in all positions of revolution of said door, and means adapted to urge said movable casing to move longitudinally away from said fixed casing.
- 85 16. In a device of the character described, in combination, a revolving door comprising a plurality of rotatable wings, a casing comprising a fixed member subtending an angle less than the angle subtended between adjacent wings and a member movable relative to said fixed member to permit 90 the edges of two oppositely disposed wings to simultaneously register with casing members in all positions of revolution of said door, and manually operative means mounted on said fixed member to prevent 95 relative movement between said fixed member and said movable member.
- 100 110 17. In a device of the character described, in combination, a revolving door comprising rotatable wings, a movable casing, means urging said casing to move in one direction, and means whereby movement of said wings effects movement of said casing in the reverse direction and increases 115 the urging force of said first mentioned means.
- 120 18. In a device of the character described, in combination, a revolving door comprising a plurality of rotatable wings, a movable casing, and means whereby rota-

tion of said wings through a predetermined arc causes said casing to move a like distance in a similar direction, and means adapted, when said wings are in a predetermined position, to cause said casing to move a predetermined distance in the opposite direction.

19. In a device of the character described, in combination, a revolving door comprising a plurality of rotatable wings, movable casings adapted to rotate independently of said wings about the axis of rotation of said wings, supports for said casings comprising a fixed member, and radiating members rotatably mounted on said fixed member and attached to said casings.

20. In a device of the character described, in combination, a revolving door comprising a plurality of rotatable wings, movable casings, a support for said casings comprising a fixed member, radiating members rotatably mounted on said fixed member and attached to said casings, and spring means adapted to urge said radiating members and said casings to rotate about said fixed member in a predetermined direction.

21. In a revolving door, in combination, a rotatable spindle, a plurality of wings mounted on said spindle, and handles mounted on said spindle and extending therefrom into the compartments between adjacent wings.

22. A casing for revolving doors comprising, in combination, a fixed portion comprising an inner member and an outer member, and a movable portion adapted to be collapsed between said inner and outer members of said fixed portion.

23. A casing for revolving doors comprising, in combination, a fixed casing comprising an inner member and an outer member, a movable casing adapted to be collapsed into said fixed casing, and means mounted on said fixed casing adapted to hold said movable casing within said fixed casing.

24. A casing for revolving doors comprising, in combination, a fixed casing comprising an inner member and an outer member, a movable casing adapted to have relative movement with respect to said fixed casing and adapted to become collapsed within said fixed casing, and means mounted on said fixed casing to limit the extent of movement of said movable casing in either direction.

25. In an apparatus of the character described, in combination, a plurality of rotatable wings, casings formed as arcs of a circle and adapted to be engaged by the edges of said wings, members associated with said casings and formed as arcs of

substantially the same circle, a mounting for said members, means for actuating said mounting to cause said members to be moved with respect to said casings to increase the space closed by the same, means actuated by said wings for causing reverse movement of said members, and means for latching said members at the termination of said reverse movement thereof, said latching means being adapted to be released at predetermined times by motion of said wings.

26. In an apparatus of the character described, in combination, a plurality of rotatable wings, casings formed as arcs of a circle and adapted to be engaged by the edges of said wings, members associated with said casings and formed as arcs of substantially the same circle, a support for said members, a spring for actuating said support to cause said members to be moved with respect to said casings to increase the space closed by the same, a plate having an aperture therein and mounted above said wings, a plunger mounted upon said support, and adapted to project normally into the path of said wings, a spring for causing said plunger to enter the aperture in said plate at predetermined positions of said support, and means controlled by movement of said wings for releasing said plunger from said aperture at predetermined positions of said wings.

27. A revolving door comprising, in combination, a vertical axis, a plurality of rotatable members symmetrically disposed about said axis, a plurality of fixed casings placed concentrically with respect to said axis and adapted to be contacted by the outer edges of said rotatable members, each of said casings subtending an angle less than that between adjacent rotatable members, a slid able member associated with each fixed casing and adapted to add to the angle subtended by the latter, a support for said slid able members, a spring actuated plunger mounted upon said support, means normally holding said plunger in the path of said rotatable members, but containing an aperture through which said plunger may be withdrawn from said path, and means for automatically restoring said plunger to normal position dependent upon the position of said rotatable members.

In testimony whereof I affix my signature, in the presence of two witnesses.

CLAUDE T. DAWES.
